Application September 30, 1941, Serial No. 412,967

3 Claims. (Cl. 24—192)

(Granted under the act of March 3, 1883, as
amended April 30, 1928; 370 O. G. 757)

This invention relates to a buckle, and has for an object to provide an improved buckle especially adapted for use on a pneumatic life-saving belt.

It is an object of this invention to provide a buckle which may be used in connection with a pneumatic life-saving belt so as to adjust the size of the belt to the individual wearing the same without any danger of puncturing the belt and destroying its efficiency for life-saving purposes.

A further object of this invention is to provide a belt buckle which may grip the pneumatic tube of the life-saving belt in such a fashion that there is no danger of injuring the tube, while at the same time it holds the tube securely so that it may remain properly about the body of the wearer.

A further object of this invention is to provide a belt buckle that may be made inexpensively, being preferably formed of flat sheet metal, suitably stamped and pressed to the desired shape, thus providing simplicity and low cost of construction and assembly. Although sheet metal is the easiest and simplest material to be used, it will be obvious that the belt may be formed of any other suitable material, including moldable plastics.

With the foregoing and other objects in view, the invention consists in the construction, combination and arrangement of parts hereinafter described and illustrated in the drawing, in which:

Fig. 1 is an elevational view of a fragment of a pneumatic life-belt with the buckle of this invention applied thereto.

Fig. 2 is a sectional view on line 2—2 of Fig. 1.

Fig. 3 is a view similar to Fig. 2, with the buckle in unsecuring position; and

Fig. 4 is an elevational view of the base of the buckle.

There is shown at 10 a hollow tube forming one end of the pneumatic life-belt to which the buckle 11 of this invention is to be applied, the other closed end of tube 10 having a plate 12 secured thereto from which extends a T-shaped tongue 14 having a transverse opening 15 through which may extend a hooked finger 16 extending from the belt securing arm 17. This arm 17 is shaped substantially as shown, being provided with a slight angular portion 18 and terminating in a rounded or cylindrically shaped end 20. Eccentric to this rounded end 20, the arm 17 is provided with a pair of oppositely extending pintles 21 about which the arm 17 may pivot, the

rounded portion 20 thus being eccentric to the journal provided by the pintles 21.

Cooperating with this arm 17 is a base member 22 having a pair of upstanding wings 23. Each wing 23 is provided with an eye 24 acting as a bearing for the pintle 21 so that the arm 17 may be pivoted about the pintles 21, and due to the eccentric mounting of the rounded end 20 and the shape of the arm 17, the rounded portion 20 approaches the base 22 most closely when the finger 16 is in a plane parallel to the plane of the base 22. Just below the eyes 24 the base 22 is provided with a rounded depression 25 which, in addition to strengthening the base 22 against bending, also cooperates with the rounded end of the clamping arm as it clamps the belt therebetween.

In operation the belt is provided with an inflating mechanism (not shown) at the closed end 20 from which the plate 12 extends. The free end of the belt 10 then is passed through the buckle 11 while the arm 17 is in the raised position shown in Fig. 3, whereby the rounded end 20 is at substantially its maximum distance from the base 22, thus permitting the belt 10 to slide freely therethrough. When the buckle has been slid along the belt the proper distance to make the belt fit the individual wearer, the arm 17 is pivoted about the pintles 21, causing its rounded end 20 eccentric thereto to press against the belt 10 and squeeze it against the base 22 and into the depression 25 as the hooked finger 16 of the arm 17 is being pivoted about its base and put through the slot 15 in tongue 14 of the plate 12 on the closed end of the belt 10. The protuberance 26 prevents accidental separation of finger 16 from tongue 14. This holds the arm 17 in the position shown with its rounded end 20 gripping the belt 10 against the base 22, thus closing off the pneumatic tube of which the belt is formed, yet due to the depression 25, which is rounded, it does not cause any tearing or puncturing action on tube 10 which, as understood, is of conventional rubberized pressure-retaining fabric. Thus, the same belt may be adjusted to fit a person of large or small girth without any danger of impairing its flotation qualities.

Other modifications and changes in the proportions and arrangement of the parts may be made by those skilled in the art without departing from the nature of the invention, within the scope of what is hereinafter claimed.

The invention described herein may be manufactured and used by or for the Government of the United States of America for governmental

purposes without the payment of any royalties thereon or therefor.

Having thus set forth and disclosed the nature of this invention, what is claimed is:

1. A device for adjustably fastening an easily puncturable inflatable belt consisting of a buckle comprising a base member having a transverse rounded depression therein strengthening the base member against bending, a clamping arm, a rounded portion on the end of said clamping arm, means for pivoting said clamping arm to said base member with said rounded portion eccentric to said pivoting means, whereby said clamping arm may move said rounded portion to and from cooperating position with the transverse depression in the base member to clamp the belt therebetween.

2. A device for adjustably fastening an easily puncturable inflatable belt consisting of a buckle comprising a base member having a transverse rounded depression therein strengthening the base member against bending, a clamping arm, a rounded portion formed on the end of said clamping arm, means for pivoting said clamping arm to said base with said rounded portion eccentric to said pivoting means, whereby said clamping arm may move said rounded portion to and from

cooperating position with the transverse depression in the base member to clamp and close off the pneumatic belt therebetween, and a hook and slot means cooperating with said clamping arm and the other end of the belt to hold said clamping arm in clamping position.

3. A device for adjustably fastening an easily puncturable inflatable belt consisting of a buckle comprising a base member having a transverse rounded depression therein strengthening the base member against bending, a clamping arm, a rounded portion formed on the end of said clamping arm, cooperating means on said arm and base for pivoting said clamping arm to said base member with said rounded portion eccentric to said pivoting means, whereby said clamping arm may move said rounded portion to and from cooperating position with the transverse depression in the base member to clamp one end of the belt therebetween, a hook on said clamping arm, slot means on the other end of the belt cooperating with said clamping arm hook to hold said clamping arm in clamping position, and a protuberance preventing accidental separation of said hook and said slot means.
